UNITED STATES PATENT OFFICE.

GEORGE D. FRAUNFELDER, OF EASTON, PENNSYLVANIA, ASSIGNOR TO EASTON CAR & CONSTRUCTION COMPANY, OF EASTON, PENNSYLVANIA, A CORPORATION OF PENNSYLVANIA.

CAR UNIT.

Application filed April 25, 1925. Serial No. 25,866.

My invention relates to dump cars in general, and particularly to that class of cars used in connection with quarry operations. All quarry cars when used for steam shovel service are subjected to tremendous shocks and strains. The load from the shovel dipper consists of large size stone and is usually discharged while the dipper is suspended high above the car body. Further, this load is very frequently dropped on the side and top edges of the body instead of on the bottom, and in quarry car construction, the car must be sufficiently rigid to prevent its being accidentally dumped or derailed from the force of such blows, either while being loaded or during transportation.

The object of my invention may be briefly summarized as consisting of the construction and combination of parts which will effectively overcome the above-mentioned difficulties common to car construction.

It is to be understood that I do not limit myself merely to the details of construction as shown, but that the scope of my invention extends to whatever construction may be defined by or included within the terms of the appended claims.

In the drawings:

Figure 1 is an end elevation of a dump car embodying my invention;

Figure 2 is a top plan view illustrating one corner thereof;

Figure 3 is a detail sectional view on the line 3-3 of Figure 2;

Figure 4 is a side elevation of my improved dump car, partly broken away; and

Figure 5 is a detail view in perspective of one of the hinged members.

My invention, in the form or embodiment shown in the drawings and briefly described, comprises a main frame, 10, a car body, 11, and aligning hinges, 12. The novel form of main frame, 10, is constructed in a substantially rectangular form and comprises the side I-beams, 13, and the centrally located channel members, 14, they extending lengthwise of the main frame. The I-beams, 13, and channels, 14, are connected at their extreme ends by means of the transversely extending channels, 15. To render the main frame very rigid in construction, I securely rivet to the upper edge of the I-beams, 13, a plurality of super-imposed and transversely extending I-beams, 16, as is

clearly shown in Figures 2 and 4 of the accompanying drawings.

My improved car body is provided with a flat bottom portion, 17, and upwardly and outwardly diverging bottom portions, 18, terminating at their outer edges in right angular bent portions, 19, as is clearly shown in Figure 3. To further reinforce these outer edges or bent portions, 19, I provide angled members, 20, each having one of its sides adjacent to the bent portion, 19, and the other adjacent to one flange of the I-beam 22 and securely riveted to both.

In order to retain the bottoms, 17 and 18, of the car body in position, regardless of the heavy shocks to which they are subjected, I employ a plurality of I-beams, 22, they being extended entirely across and conforming to the contour of the bottom of the body, 11. The I-beams, 22, are suitably riveted to the bottoms, 17 and 18, by means of rivets, 23. The angle members, 20, are sufficiently spaced from the bottoms, 18, to permit the side, 21, of the angle, 20, to bear against the lower leg of the I-beam, 22, to which it is securely fastened by means of the rivets, 24.

The ends, 25, of the car body are secured in position by means of rivets and are reinforced at their upper edges by means of the angled strips, 26, which are also riveted thereto. Corner strips or members, 27, are extended between the angled strips, 26, and the angled bent portions, 19, and securely riveted thereto.

It will be readily understood with particular reference to Figures 1 and 4 that the I-beams, 16 and 22, are of the same height. By means of this novel arrangement, the lower edges of the central portions of the I-beams, 22, rest upon the longitudinally extending members, 13 and 14, whereas the bottom, 17, is firmly seated on the upper faces of the transversely extending I-beams, 16. This construction, it will be readily seen, affords a very rigid and substantial support for the body and will effectively prevent any twisting, buckling or straining of the body with respect to the main frame support.

For the purpose of effectively absorbing all unnecessary jars or shocks from the bottom, 17, of the car body, I provide a plurality of longitudinally extending strips of

wood, 29, and a steel plate or super-imposed bottom, 30, as is clearly indicated in Figures 1 and 2. These strips or planks, 29, together with the supplemental bottom, 30, may, of course, be readily removed as for replacement or according to the nature of the work.

The novel form of hinge in connection with my improved dump car illustrated in Figures 1, 4 and 5, consists primarily of two sections; 10 relatively stationary sections or brackets, 32, which are securely riveted at the corners of the main frame, 10, and relatively movable members, 33, which are riveted to the lower sides of the body, 11.

15 The brackets, 32, of the hinge, 12, are each preferably cast and consist of a pair of vertically extending right angular flange members, 35 and 36, and a horizontally disposed flange, 37. Extending upwardly from the flange, 37, are a pair of integrally cast end walls or ears, 38, which are connected by means of the side walls, 39, and 40, for the purpose of forming a substantially semi-circular recess, 41. Openings, 42, are concentrically disposed through the end walls or ears, 38, for a purpose to be later described. The flanges, 35, 36 and 37, are provided with suitable openings for the purpose of being riveted to the I-beams, 13, and 20 the channel members, 15. These right angular flanges, 35 and 36, it will be readily seen, serve as corner locking means by reason of their being secured to the adjacent corners of the main frame, 10.

25 35 Snugly fitting within each of the semi-circular recesses or depressions, 41, is a substantially cylindrical member, 43, which is cast or otherwise formed integrally with a pair of angularly disposed flanges or plates, 44 and 45, and reenforced by a suitable rib, 46. The included angle between the flanges or plates, 44 and 45, is, of course, identical with the angle of the bottoms, 17 and 18, of the car body, to which the flanges are suitably riveted.

40 45 By reason of the cylindrical hinge members, 43, fitting into their respective recesses or depressions, 41, the car body is firmly held into its seated position regardless of the fact that the dump car is fully loaded or empty. All end and side thrusts of the body are, of course, taken up by the cylindrical members 43 of bracket 33 moving against the end wall 38 of bracket 32. Should it be further 50 55 desired to lock the car body to its supporting frame, I have provided a pivot pin, 47, for each pair of hinge members, 12, with a slightly tapered nose on its inner end and an eye on its enlarged outer end, for the purpose 60 65 of connection by means of a chain or the like to the car, the said pin being introduced through the apertures, 42, and a concentric aperture in the member, 43.

65 There are instances where I have found it desirable to invert or rather reverse the po-

sition of the hinge members, 12, with respect to the main support, 10, and the car body, 11; that is to say, the portion of the hinge provided with the semi-circular recess or depression would be secured to and carried by the relatively movable car body, whereas the substantially cylindrical or male portion, 43, would be carried by the main supporting frame. By this arrangement, it will be readily seen, that stones or foreign matter will not be retained within the semi-circular depression and prevent the entering and seating of the cylindrical portion, 43, within its mating recess, 41.

70 75 Rigidly secured upon the outer edge of each side of the car body and in the approximate center thereof, is a lifting device, 50, as is clearly indicated in Figures 1 and 4. Each of the lifting devices consist of a pair of similarly formed castings or the like, each provided with a pair of right angular flanges, 51, which are provided with openings for the purpose of riveting to the outer edge of the box girder construction and to the angular members, 21, to carry beams, 22, and in 80 this manner, all pull is on the I-beams, 22, instead of plate 18. These castings are further provided with a pair of aligning hub portions, which are provided with central openings for the purpose of receiving a lifting arm or rod, 52. The angularly formed flanges, 51, of the lifting devices being riveted to the outer and under sides of the box girder construction provide a very rigid means for tilting the body of the car.

85 90 95 It is to be understood, of course, that although it has been found from actual tests under the most severe working conditions that an all-steel car built in accordance with my invention, is highly efficient, economical and practical, yet beams of wood may be substituted in place of the I-beam floor supports, 16, if I so desire.

100 When it is desired to dump my improved car, one of the sets of aligning pivot pins, 47, are removed from the apertures, 42, which had been inserted through the concentric opening in each of members, 43, for locking the car body to the supporting frame.

105 A hoist is then attached to the rod 52 of 110 the lifting device 50, located on that side of the car to be raised, that is, adjacent the disconnected hinge 12.

I claim:

110 1. A dump car, comprising a frame, a car body, a plurality of transversely extending beams secured to the lower side thereof and a plurality of hinges, each comprising a substantially cylindrical portion, a member having a semi-circular depression and a removable pivot pin.

115 2. A dump car, comprising a frame, a plurality of transversely extending beams securely mounted upon the frame, a car body having a plurality of beams secured to and 120

extending across the entire width of the under side of said car body and a plurality of hinge members, each having a substantially semi-circular depression, a mating cylindrical portion and a removably mounted pivot pin for locking said hinged members.

3. A dump car, comprising a frame, a car body, having a substantially flat bottom and upwardly and outwardly inclined sides, a plurality of transversely extending beams conforming to said car body and secured thereto, and adapted to rest upon said frame and a plurality of oppositely disposed and aligning hinges, for permitting the tilting of the car body with respect to the main frame.

4. In a dump car, having a main frame and a car body, a plurality of hinges located on either side of the car body, each of said hinges comprising a bracket having a semi-circular depression on its upper end, a cylindrical portion adapted to snugly fit within said depression and a removably mounted pivot pin for locking said hinged members.

5. In a dump car, having a main frame and a car body, a plurality of hinges located on either side of the car body, each of said hinges comprising a bracket having a semi-circular depression on its upper end, a cylindrical portion adapted to fit within said depression and a removably mounted pivot pin for locking said hinge members.

6. In a dump car, having a main frame and a car body, a plurality of hinges located on either side of the car body, each of said hinges comprising a stationary bracket having a semi-circular depression on its upper end, a removably mounted cylindrical portion adapted to fit within said depression and a removably mounted pivot pin for locking said hinged members.

7. A dump car, comprising a main frame,

a plurality of transversely extending beams secured thereon, a movable car body adapted to rest thereon, a plurality of transversely extending supporting beams carried by and secured to the lower side of the car bottom, the central portions thereof adapted to rest upon said main frame and a plurality of hinges, portions of which being secured to the main frame and mating portions of said hinges being secured by the car body.

8. A dump car, comprising a frame, a car body, having a substantially flat bottom and upwardly and outwardly inclined sides, a plurality of transversely extending beams conforming to said car body and secured thereto, the extreme ends of said inclined sides of the bottom projecting slightly beyond the extreme ends of the transversely extending supports, longitudinally extending reinforcing means for said edges and a plurality of hinges located on either side of the car body, each of said hinges comprising a bracket having a semi-circular depression, a cylindrical portion adapted to snugly fit into said depression, and a removable pivot pin for locking said hinge.

9. In a dump car having a main frame and a car body mounted thereon, consisting of a horizontal bottom and upwardly and outwardly diverging side portions integral therewith, a removably mounted metallic bottom spaced from first-named horizontal bottom by means of a plurality of longitudinally extending cushioning beams.

10. A dump car, comprising a flat bottom, upwardly and outwardly diverging side portions, an auxiliary metallic bottom spaced from first-named bottom and a plurality of longitudinally extending cushioning members located between said first-named bottom and the auxiliary bottom.

GEORGE D. FRAUNFELDER.
